TOBACCO LATH PULLER

Charles H. Weidman, Sr., Manheim, Pa.

Application April 28, 1942, Serial No. 440,871

2 Claims. (Cl. 214—5.5)

The present invention relates to improvements in machines for withdrawing laths or similar supports from tobacco stalks.

It is presently customary to suspend tobacco from laths or similar supports in the process of drying. The removal of the tobacco, after curing, presents a problem which my invention is designed to improve.

The primary object of the invention is to provide a device that will materially facilitate the removal of the tobacco from the lath or similar support.

Another object of the invention is to provide a device of this character that is simple in construction, relatively inexpensive to manufacture and particularly effective and rapid in operation.

The invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

In the drawing:

Figure 1 is a side elevational view of a lath pulling machine embodying the features of the present invention.

Figure 2 is an end elevational view thereof.

Figure 3 is a top plan view thereof.

Figure 4 is a vertical sectional view taken substantially on line 4—4 of Figure 2.

Figure 5 is a side elevational view illustrating the machine in use.

Referring to the drawing for a more detailed description thereof, the improved machine is generally designated by the reference numeral 8 and includes a base 9 and plant holding member 10 which extends upwardly from the rear end of the base and is attached thereto by any desired means. The base 9 and member 10 may be made of wood or any other material suitable for the purpose, the base 9 adapted to be mounted upon and secured to a table or other suitable support 11, as shown in Figure 5 of the drawing.

The lath pulling means includes upper and lower rollers 12 and 13 respectively, maintained in spaced relation and adapted to rotate in opposite directions. The lower roller 13 is mounted on a shaft 14, the ends of said shaft being journaled in supports 15 which are attached to and extend forwardly of the holding member 10. A grooved pulley 16 is mounted on the shaft 14

for effecting rotation of said shaft and roller 13. As best shown in Figure 5 of the drawing, an electric motor 17 of conventional construction is bolted or otherwise secured to the base 9 and its armature shaft 18 has a pulley 19 mounted thereon. The pulleys 16 and 19 are united by means of a belt 20 whereby rotation of the armature shaft 18 will rotate said pulleys to drive the shaft 14.

The upper roller 12 is rotatably mounted upon a shaft 21 carried by a U-shaped support 22. The shaft 21 is fixed to the front ends of the sides 23 of the support 22 and the cross bar 24 of said support is connected by means of bolts or the like 25 to the front face of the plant holding member 10. As shown in Figure 4 of the drawing, the bolts 25 are mounted below the center of the cross bar 24 and have coil springs 26 held thereon by means of nuts 27. This construction permits the upper roller to yield upwardly, as shown in dotted lines, whereby to adapt the machine for pulling laths of different thicknesses.

The member 10 is provided with an opening 28 through which the laths are inserted to be pulled through the machine by means of the rollers 12 and 13. The rollers in turn are so arranged with relation to the opening 28 that they will engage the end of the lath inserted within the rollers thereby pulling the lath as the member 10 holds the tobacco plants, to effect removal of the plants from the lath. The rollers 12 and 13 are preferably formed with a corrugated external surface as indicated at 29 to create a greater frictional contact with the laths.

The shaft of each roller carries a spur gear 30 and 31 respectively, the spur gear 31 being mounted on the shaft 14 on the inside of the pulley 16. The meshing of the gear 30 with the gear 31 will drive the roller 12 thereby affording an increased pulling grip on the lath. The spurs on the gears are relatively long to compensate for the rollers being spread-apart on account of the various thickness of the lath.

From the above description when taken in connection with the accompanying drawing, it is believed that the operation of the machine is readily apparent. As shown in Figure 5, the lath 32 on which are supported the stalks of tobacco 33, is inserted through the opening 28 in such a manner that the tobacco is disposed in a horizontal position. The motor 17 is operated to drive the rollers 12 and 13 in the manner previously described and when said rollers are engaged by the lath, it will be pulled entirely through the opening 28. As the lath is moved

through the rollers, the tobacco will be held by the member 10 and, upon complete removal of the lath, will fall to the table 11. This means of removing the tobacco from the lath is relatively rapid and injury thereto is substantially precluded.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the invention nor exceed the scope thereof as expressed in the appended claims.

What is claimed is:

1. In a lath pulling machine a support having a vertical section provided with a lath receiving opening, a transversely disposed roller rotatably mounted on the support, a member having parallel side portions projecting from the

5 vertical support section, an auxiliary roller rotatably supported on the said side portions in position to co-operate with the first mentioned roller for pulling a lath through the said opening, and means resiliently connecting the said member to the vertical support section whereby to allow resilient elevation of the side portions and roller carried thereby.

2. In a lath pulling machine including a base, 10 a member attached to said base and extending upwardly at right angles thereto, said member formed with an opening through which one end of a lath is inserted, a pair of supports secured to said member, a roller carried by said supports, 15 a U-shaped member mounted on said vertical member above said supports, a roller carried by said U-shaped member and held in spaced relation above said first mentioned roller with said rollers disposed in front of said opening, and 20 means for securing said U-shaped support to said vertical member whereby its roller will yield upwardly to adapt the machine for pulling laths of different thicknesses.

CHARLES H. WEIDMAN, SR.
